UNITED STATES PATENT OFFICE.

ERIDA RIOTTE, OF SCHLETTSTADT, GERMANY.

AIRSHIP.

1,121,762.

Specification of Letters Patent. Patented Dec. 22, 1914.

Application filed July 5, 1913. Serial No. 777,546.

To all whom it may concern:

Be it known that I, ERIDA RIOTTE, a subject of the German Empire, residing at Schleettstadt, Germany, have invented certain new and useful Improvements in Airships, of which the following is a specification.

This invention relates to an airship which comprises in combination a flying machine and a gas balloon, the gas balloon being used to balance approximately the weight of the airship and being arranged between lateral balloons capable of being gradually filled to facilitate the ascent and retention of the airship in equilibrium. The gondola or car for the passengers has an outer covering in the form of gas tubes which are employed on the one hand as reservoirs for compressed gas for use in filling the lateral balloons during the ascent to insure an ascent as vertical as possible, and also for subsequently filling them while traveling, and on the other hand to form a cushion or buffer which in the event of a sudden landing will minimize any shock and render the landing safe and smooth. A resilient skid is provided below the car and adapted to coact with the gas tubes thereon in order to assist in the initial ascent from the ground and also to insure a safe landing. The airship therefore, permits of ascent and landing without necessitating the assistance of a skilled pilot.

In addition to the foregoing, the under-sides of the lateral balloons have a particular formation which renders them capable of acting as aeroplanes or supporting surfaces when the airship is caused to travel forward under the action of a suitable propeller so that safe flight with balloons of comparatively small volume is rendered possible. The complete airship consequently forms a particular combination producing an apparatus possessing a high maneuvering capacity. Owing to the gas tubes covering the car a descent on water is rendered possible.

The accompanying drawing illustrates by way of example an airship according to the invention, Figures 1 and 2 being respectively a side elevation and a front elevation. Fig. 3 is a diagrammatic plan on a smaller scale showing the outlines of the three balloons and indicating the relative positions of the louver rudders.

The airship illustrated consists of a cen-

tral gas balloon *a*, of known form. To this are laterally connected two special balloons *b*, which, however, are organically connected to the balloon *a*, and stiffened by transverse supports *c*, and ties *d* in such a manner, that their under surfaces *x*, form two lateral wing-like supporting surfaces for the balloon *a*, which surfaces are downwardly inclined toward the rear. The under surfaces form in effect aeroplanes. A current of air produced by an air propeller *g*, therefore, strikes on both sides upon these supporting surfaces *c*, *d* and causes the whole airship to ascend. It is essential that the current of air should be effectively distributed to the right and to the left by the cylindrical balloon *a*, upon the supporting surfaces, and consequently a single air propeller suffices for the entire flying apparatus; two air propellers can be employed if desired. The air propeller can be driven by any suitable means and can also be arranged somewhat higher. The drive, in the constructional example illustrated, is effected by chain transmission *f*, from the motor which is mounted in the front of the gondola or boat-like car. The car is closed in on all sides and is capable of floating. This is also assisted by the air-tubes *h*, of which any suitable number are provided around and under the car, and which are advantageously in communication with one another and, on the one hand, are fitted with valves *i*, through which they may be filled with hydrogen gas and the like and, on the other hand, are connected to the balloons *b*, by hand operated closure members or valves *k*, and tubular conduits *l*. The gas compressed or pumped into the tubes *h*, forms a cushion underneath and around the car which insures a resilient landing of the car on the ground and a better floating capability. A starting skid *o*, is arranged below and when strained is free to bear against the resilient gas cushion so that it facilitates starting and permits of landing without shock.

The supporting surfaces *c*, *d*, have rearward louver extensions or rudders *m* and *n*, which can be operated and adjusted from the driver's seat by cables or other tension members *r*, so that duplicate steering is possible and this also as these flaps are provided in two separate sets relatively disposed at an obtuse angle (Fig. 3). Steering for ascent or descent is obtained when all the

flaps are adjusted at an angle, and lateral steering when only one set of flaps, either m or n , is adjusted. In this manner means are provided for effectively meeting lateral 5 wind disturbances. The breadth and length of the flaps may be varied; short outer flaps would suffice. For exhausting the gas the balloons may be in the usual manner provided at the top with hand operated exhaust valves.

When first filling the lateral balloons the usual gas, for example, from steel bottles, is employed, the bottles being connected to the gas tubes h , which thus form intermediary 10 holders for conducting the gas from the bottles into the balloon and serve as pressure regulators. While traveling, the compressed gas in the tubes h , can at any time be employed for subsequently filling the gas balloons and these tubes permit of a safe, and 15 rapid subsequent filling.

This airship can ascend without the assistance of skilled pilots. It is also well suited as an ocean airship as a subsequent 20 filling with gas is possible at any time.

I claim:

1. An air ship comprising in combination a central gas balloon, a lateral gas balloon parallel with and located on each side of the 30 central gas balloon, the bottoms of the lateral two gas balloons being horizontal and in the same plane, the horizontal bottoms of the lateral balloons extending from the front end of the central balloon then curve upwardly and thence are inclined downwardly and terminate at the rear substantially in alignment with the bottom of the central balloon, rudders at the rear ends of the lateral balloons, a propeller, a car, and means on 40 the car for operating the rudders and the propeller.

2. An airship comprising in combination, a central gas balloon, lateral gas balloons arranged alongside of and connected to the 45 central gas balloon, having under surfaces forming aeroplanes, said aeroplanes being in a horizontal plane with the central balloon, a car for passengers, gas tubes placed around the sides and bottom of said car the 50 tubes being arranged transversely of the car, means for conducting gas from said gas tubes to the aforesaid balloons, and means for propelling said airship.

3. An airship comprising in combination, 55 a central gas balloon, lateral gas balloons arranged alongside of and connected to the central gas balloon having undersurfaces forming aeroplanes said aeroplanes being in a horizontal plane with the central balloon, 60 a car for passengers, gas tubes on said car for supplying the aforesaid balloons with gas during flight, a resilient skid on the

underside of said car for facilitating initial ascent and landing, and means for propelling said airship, substantially as and for the 65 purpose hereinbefore set forth.

4. An airship comprising in combination, a central gas balloon, lateral gas balloons having undersurfaces forming aeroplanes, transverse supports and ties for connecting 70 said balloons, louver rudders at the rear of the lateral balloons, a passenger car, means operable on the car for operating said louver rudders, means on the car for supplying said balloons with gas during flight, and 75 means for propelling said airship substantially as and for the purpose hereinbefore set forth.

5. An airship comprising three gas balloons two of said balloons being arranged 80 symmetrically one on each side of the third, and having undersurfaces forming aeroplanes, a boat-shaped passenger car, gas tubes outside said car and on the sides and bottom thereof, a conduit between said tubes 85 and the aforesaid lateral balloons, a hand valve on said conduit, louver rudders at the rear of the lateral balloons for steering the airship both laterally and vertically, and a propeller for throwing a current of air on to 90 the under surfaces of the lateral balloons and for propulsion purposes, substantially as and for the purpose hereinbefore set forth.

6. An airship comprising in combination a central gas balloon, lateral gas balloons 95 having under surfaces forming aeroplanes, a car, gas tubes surrounding the sides and bottom of said car and adapted to act as gas regulators and gas feeders for the filling of the balloons, said gas tubes also acting as 100 cushions for facilitating landing without shock and as buoyant bodies for supporting the car on water.

7. An airship comprising a central elongated gas balloon, aeroplanes on each side of 105 said central gas balloon, the aeroplanes extending from the front end of the balloon and curving upwardly and then inclining downwardly and terminating at the rear lower portion of said balloon, rudders at the 110 rear end of said aeroplanes, lateral gas balloons mounted on top of the aeroplanes alongside the central gas balloon, a car suspended from the aeroplanes, means carried by the car to supply the balloons with gas, 115 means in the car for operating the rudders, and a propeller for propelling the airship.

In testimony whereof I have signed my name to this specification in the presence of two subscribing witnesses.

FRIDA RIOTTE.
